UNITED STATES PATENT OFFICE.

KARL A. T. JOHANSSON, OF DETROIT, MICHIGAN.

CARBURETOR.

Application filed April 10, 1922. Serial No. 550,950.

This invention relates to improvements in carburetors and has for its principal object the provision of a carburetor whereby the proportionate mixture of air and hydrocarbon vapor will be maintained substantially constant at varying speeds of the engine.

A further object of my invention is to provide a simple and effective means of creating a subatmospheric pressure in the fuel reservoir with automatic controlling means to limit the extent of the drop in pressure.

The above and other objects of my invention will be apparent from the following description wherein reference is made to the accompanying drawing illustrating a preferred embodiment of my invention, and wherein similar reference numerals designate similar parts throughout the several views.

20 In the drawings:—

Fig. 1 shows a side elevation of an engine with my improved carburetor in position thereon;

Fig. 2 is an enlarged central sectional view through the carburetor, and

Fig. 3 is a detail section through the aspirating jet and associated parts, taken substantially on the line 3—3 of Fig. 2.

Referring now to the drawing the numeral 30 5 designates an internal combustion engine of any desired construction having an intake manifold 6 leading from the supply tube 7 of the carburetor 8 to the several cylinders of the engine. The carburetor 8 35 is preferably secured to the lower extremity of the intake manifold by bolts 9 passing through apertured flanges 10 on the carburetor and manifold respectively.

The carburetor 8 is preferably constructed 40 with a constant level fuel-chamber 11 having an intake opening 12 in its lower wall adapted to be connected with the pipe line 13 leading to a fuel tank (not shown). A needle valve 14 is adapted to close the inlet 45 opening 12 when the fuel in the chamber 11 has reached the desired height, the valve 14 being controlled by a float 15 and levers 16 pivoted intermediate their ends upon the upper wall of the fuel-chamber, substantially 50 as shown in Fig. 2. One arm of each lever 16 is engaged by the float 15 while the other arm of each lever engages a collar 17 on the needle valve 14, whereby the upward movement of the float incident to a rise in 55 the level of the liquid in the fuel-chamber will serve to force the needle valve 14 down-

wardly to close the inlet opening 12. The fuel-chamber 11 is connected, as by the passage 18, with the central bore 19 of the aspirating jet 20, best shown in Fig. 3. The 60 jet 20 is preferably so located relatively to the fuel-chamber that the liquid in the aspirating jet and fuel-chamber is normally at the height indicated by the dotted line A in Fig. 2, with the liquid almost filling the 65 bore 19 of the jet. The air adapted to be mixed with the fuel carried in the jet 20 is adapted to enter at the air-intake pipe 21 and passes around the upper extremity of the jet 20 into the mixture-supply pipe 7 of 70 the carburetor, a Venturi tube action being secured by reducing the area of the lower extremity of the mixture-supply pipe 7 adjacent the top of the jet 20 and then gradually widening the area of the mixture-supply 75 pipe above the jet 20. To adjust the effective area of the air-intake pipe 21 and the mixture-supply pipe 7, I preferably construct the inclined lower portion of the supply pipe 7 in a rotatable member 22 pivotally mounted in the side walls of the carburetor on pivots arranged in a plane slightly below the upper terminal of the jet 20. A lever arm 23 is fixed upon the projecting 80 end of one of the pivots of the member 22 and connects with a rod 24 leading to the throttle-control lever on the steering wheel or to some other location convenient to the driver of the automobile or other vehicle using the engine 5. The lower portion of 85 the rotatable member 22 is hollowed out to form an air passage 22^a normally forming a continuation of the air-intake pipe 21, and the solid portion of the member 22 is arranged substantially as shown in Fig. 2 so 90 that upon rotation the solid portion of the member 22 will swing across and so reduce the effective area of the air-intake pipe 21 simultaneously with the reduction of the effective area of the mixture-supply pipe 7. 100 By virtue of this construction I am able to control the admission of air to the carburetor so that a mixture will be supplied to the engine cylinders sufficiently rich in fuel to start the engine and maintain it running at 105 any desired speed.

To regulate the supply of fuel into the jet 20 at varying speeds of the engine, I provide means for producing a sub-atmospheric pressure in the fuel-chamber 11 above the 110 surface of the liquid therein, a passage 25 leading from the upper portion of the

fuel-chamber 11 to the bore of a tube 26 preferably surrounding the jet 20, substantially as shown in Fig. 3. At its upper extremity the tube 26 is inclined to receive a cap 27 having arranged at one side thereof one or more horizontally extending openings 28 leading to the bore of the tube 26, and in the opposite side thereof, one or more inclined apertures 29 leading upwardly into the bore of the tube 26 (see Fig. 3). With this construction the air drawn by the upper terminal of the aspirating jet 20 by the suction of the engine, will produce an entraining effect tending to exhaust the air in the upper portion of the fuel-chamber 11 through the bore of the tube 26 and passageway 25, the air being drawn out through the horizontal openings 28. The inclined openings 29 are so located as to prevent an excessive exhaustion of the air in the fuel-chamber 11 because of their arrangement in the path of the air entering through the air-intake pipe 21, the in-rushing air passing through the inclined openings 29 to assist in breaking the partial vacuum in the tube 26. The area of the inclined openings 29 and the horizontal openings 28 may be so regulated as to produce a reduction of atmospheric pressure in the fuel-chamber 11 corresponding to the amount of fuel mixture needed by the cylinders of the engine 5 at varying speeds, the resultant mixture maintaining a substantially constant proportion of air and fuel regardless of the speed of the engine.

As herein shown the aspirating jet 20 is provided adjacent its lower extremity with a flange 30 adapted to rest upon the lower wall of the opening 31 in the bottom wall 40 of the carburetor, into which opening the

fuel passageway 18 opens. The upper portion of the opening 31 is threaded to receive the threaded lower extremity of the tube 26, which is provided with a shouldered portion 32 above the threaded portion adapted to seat firmly against the lower wall of the carburetor to prevent leakage of air into the tube at this point.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claim.

Having described my invention, I claim:

The combination with a carburetor having a constant level fuel-chamber and an intake passage, of an aspirating nozzle extending into the intake passage and connected with the fuel-chamber, means for producing a sub-atmospheric pressure in the fuel-chamber above the liquid therein, comprising a tube surrounding the nozzle and connected by an air passage with the upper portion of the fuel-chamber, the tube having a series of openings adjacent its upper extremity arranged so that the passage of the fuel mixture through the intake passage will exhaust the air from the tube, and the tube having a second series of openings of lesser area than the first-mentioned series arranged to admit fuel mixture into the tube to restrict the extent of depression of such sub-atmospheric pressure.

In witness whereof I hereunto set my hand.

KARL A. T. JOHANSSON.
